DESIGN FOR A GAME BOARD

Herman Barna, St. Paul, Minn.

Application July 18, 1936, Serial No. 63,932

Term of patent 3½ years

To all whom it may concern:

Be it known that I, Herman Barna, a citizen of the United States, residing at 1445 Ashland Avenue, in the city of Saint Paul, county of Ramsey, and State of Minnesota, have invented a new, original, and ornamental Design for a Game Board, of which the following is a specification, reference being had to the accompanying drawing, forming part thereof.

I claim:

The ornamental design for a game board, as shown.

HERMAN BARNA,
